SEALED PACKAGE

John J. Pahls and Adolph C. J. Tamm, St. Louis, Mo., assignors to Anchor Cap & Closure Corporation, Long Island City, N. Y., a corporation of New York

Application January 12, 1935, Serial No. 1,460

5 Claims. (Cl. 215—37)

The present invention relates to sealed packages, and more particularly to an applicator package and the parts thereof.

Various products, such as perfume, iodine, mer-
5 curochrome, medicinal preparations, and the like, are preferably applied in small quantities by a suitable applicator device which may be combined with the sealing cap. A popular construction comprises a glass applicator rod attached
10 to a closure cap or stopper so that the consumer can use the cap or stopper as a handle for the rod when applying the product. Such a construction is objectionable because frequently the applicator rods work loose from the cap and are
15 lost. Another difficulty is that the glass rods break and fall into the product, thus rendering the product unsafe for further use. Also, the cost of the rods and the cost of securing them to the caps substantially increases the cost of the
20 package. Attempts have been made to eliminate the use of applicator rods by packing the product in bottles having a relatively small opening which permits the product to be applied directly from the bottle, but these attempts have been unsuc-
25 cessful because such bottles are difficult to make and must be filled by special machinery.

The present invention aims to overcome the above objections by providing an applicator member adapted to be attached to the container for
30 applying the product directly in small quantities, and further aims to provide a closure cap adapted to cooperate with the applicator member to seal the package.

An object of the invention is to provide a simple
35 inexpensive applicator package.

Another object of the invention is to provide an applicator package for applying the product directly from the container in small quantities.

Another object of the invention is to eliminate
40 the use of applicator rods.

Another object of the invention is to provide an applicator package which, when opened, may be upset accidentally without spilling the contents.

45 Another object of the invention is to provide an applicator container adapted to be filled and sealed quickly and conveniently without the use of special machinery.

Another object of the invention is to provide a
50 container with an applicator member which also serves as a sealing member.

Another object of the invention is to provide an applicator package made of durable parts not subject to corrosion or breakage.

55 Another object of the invention is to provide

an applicator member which may be applied to various shapes and types of bottles.

A further object of the invention is to reduce the cost of assembling the parts of applicator packages.

Other and further objects of the invention will be obvious upon an understanding of the illustrative embodiment about to be described, or will be indicated in the appended claims, and various advantages not referred to herein will occur to one skilled in the art upon employment of the invention in practice.

A preferred embodiment of the invention has been chosen for purposes of illustration and description and is shown in the accompanying drawing, forming a part of the specification, wherein

Fig. 1 is an exploded perspective view of a pre-
ferred embodiment of the invention;

Fig. 2 is a sectional view of a sealed applicator
20 package;

Fig. 3 is a sectional view showing the product in the package being applied directly to the wound;

Fig. 4 is a fragmentary sectional view showing
25 another embodiment of the invention; and

Fig. 5 is a fragmentary sectional view of still
another embodiment of the invention.

Referring again to the drawing and more par-
ticularly to Figs. 1 and 2, there is shown a con-
30 tainer 1 having a body 2 and a neck 4. The neck preferably is provided with screw threads 5 or other means for engaging threads on a closure cap adapted to be sealed on the container, and is provided at its upper end with a rim 6 extend-
35 ing about the opening or mouth 7 of the con-
tainer. If desired, a bead or shoulder 9 may be provided beneath the threads 5 to improve the appearance of the package.

In order to provide a simple and inexpensive
means for dispensing the product, a suitable
40 applicator member 10, preferably made of non-
corrosive material, for example, sanitary rubber,
is attached to the container. The applicator member preferably comprises a tubular or cylind-
45 rical part 11 adapted to be forcibly inserted into the neck opening 7 of the container to attach it thereto, and a flange portion 12 adapted to lie over and engage the rim 6 of the container. The top portion of the insert adjacent the central
50 aperture may be raised slightly, as shown in the drawing, to facilitate direct application of the contents. The raised portion is also adapted to be pressed downwardly by the cover portion of the cap to cause the projection 21 of the cap to
55

be more securely engaged. A suitable aperture having a relatively small diameter or a capillary opening 14 is provided at the top of the applicator member for dispensing the product from the container drop by drop as described hereinafter, or in small quantities by direct contact with a wound. The opening 14 is enlarged at its lower end and tapers downwardly and outwardly to form a substantially cone-shaped recess 15 for passage of the product from the container to the aperture 14. By reason of the small aperture 14 the product may be ejected drop by drop by tapping or shaking the container. If the top of the insert is rubbed gently against a surface or wound, as illustrated in Fig. 3, a thin film of the contents will be applied. The aperture is preferably too small to permit the contents to flow out when the container is inverted or upset accidentally. The insert 10 may also be utilized to provide a shaker top for dispensing hair tonics and the like by enlarging the aperture 14 therein.

A closure cap 16, preferably molded of a phenolic condensation product or the like, is provided for sealing the container. If desired, the cap may also be made of other material such as tin plate or lead alloys commonly used for collapsible tubes and the like. The cap may comprise a cover portion 17 and a depending skirt 19 having threads 20 for engaging the threads of the container or may be provided with other suitable means for attaching it to the container. When the cap is screwed on the container, the underside of the cover part engages the flange portion 12 of the applicator member 35 and presses the flange downwardly against the rim 6 to seal the package.

In order to close the aperture 14 in the applicator member 10, the underside of the cover part 17 of the cap is provided with a downwardly depending projection or plug shaped portion 21 adapted to fit into the aperture 14. Preferably, the diameter of the projection 21 is slightly greater than the diameter of the aperture to securely seal the aperture, and the free end 22 of the projection is tapered or rounded to facilitate insertion of the projection into the aperture when the cap is applied. In addition, to sealing the aperture 14, the projection 21 prevents clogging of the aperture and assures uniform application of the contents at all times. The plug 21 preferably is molded or formed integral with the cover part of the cap to reduce the cost and simplify the manufacture of the device, but in some instances, it may be desirable to separately attach a plug member to the cap.

In Fig. 4 another embodiment of the invention is shown wherein a suitable disc 25 of Cellophane, rubber or the like is cemented or otherwise secured to the rim 6 of the container and a dispensing aperture 26 is formed at the center of the disc. This construction reduces the cost of the packing and minimizes the labor required in filling and sealing the bottle.

In Fig. 5 a cap 30 is shown made of sheet metal such as aluminum coated tin plate or the like. Suitable threads 31 are provided in the skirt for engaging corresponding threads on the container and a bead or wire edge 32 is formed at the lower edge of the skirt to conceal the raw edge of metal. The cover part of the cap is provided with downwardly depending projection 33 adapted to extend into and seal the aperture 14 of the dispensing member 10. The projection 75 may readily be formed in the cover part of the

cap during manufacture thereof by any suitable punching or drawing operation without increasing the cost of the cap or the amount of metal required to make the cap. If desired, an annular downwardly depending sealing rib 34 may be provided in the cover part for engaging the flange 12 of the dispensing member 10 to press it against the rim whereby a secure seal is formed between the cap and the container. Caps made of metal may be more desirable in some instances since they are less expensive than molded caps and can be readily manufactured by automatic machinery.

An important advantage of the present invention is that all the parts of the package can be made by existing machinery, for example, standard containers may be utilized while the caps can be molded or rolled in any conventional manner. The applicator member 10 or the disc 25 may also be formed inexpensively from rubber or other suitable material adapted to provide a seal. The packages preferably are provided by filling the containers with the product, inserting or attaching the dispensing members to the containers, and thereafter applying the closure caps. These operations may be readily performed manually or by automatic machinery.

In using the package, the cap is first unscrewed from the container to withdraw the sealing projection from the dispensing aperture 14. The bottle is then inverted and may be tapped lightly to eject the product through the aperture drop by drop. The product may also be dispensed by pressing the applicator member against the part to which the product is to be applied so that capillary action or adhesion causes the product to flow out in a thin film. If the package is upset accidentally while the cap is removed, only a drop or two of the product is spilled. This is an important advantage since the entire contents would be lost from packages having the usual mouth opening. The insert 10 may also be utilized to provide a shaker top for dispensing hair tonics and the like by enlarging the aperture 14 therein.

It will be seen that the present invention provides a simple inexpensive applicator package made of a minimum number of parts, which are readily assembled. Since the sealing projection is preferably formed integral with the cap, no additional assembling operation is required. The small opening permits the product to be economically applied directly from the container in small quantities. Also, if the bottle is upset accidentally, the contents will not be spilled thus eliminating the danger of damaging the consumer's clothing. The closure cap cooperates with the dispensing member to provide a secure seal without the use of additional sealing members and in addition prevents the dispensing aperture from clogging. The parts of the package are rugged in construction and can readily withstand any rough usage to which they may be subjected.

As various changes may be made in the form, construction and arrangement of the parts herein shown and described without departing from the spirit and scope of the invention and without sacrificing any of its advantages, it is to be understood that all matter herein is to be interpreted as illustrative and not in a limiting sense.

Having thus described our invention, we claim:

1. A sealed package comprising, in combination, a container having a rim and screw threads below the rim, a substantially flat resilient disc

adhered to said rim having a relatively small aperture therein for dispensing the contents of the package drop by drop, and a closure cap having a skirt provided with screw threads for engaging the screw threads of the container and having a cover portion adapted to engage and compress the disc to seal the package, said cap having a projection on the underside of said cover portion adapted to extend into said aperture to seal said aperture.

5 2. A sealed package comprising, in combination, a container having a screw thread, a resilient member secured to said container, said member having a portion fitting against the rim 10 of said container and having a duct extending longitudinally therethrough, the upper end of said duct being of capillary dimensions for a short portion only thereof, said portion with the capillary dimensions terminating flush with the 15 upper end of said resilient member to facilitate application of the contents to a wound by direct contact of the upper end of the resilient member therewith, the portion of the duct below said capillary end being larger to form a cavity to 20 facilitate the flow of the fluid to the capillary end, and a screw closure cap having a substantially cylindrical projection forced into the capillary end of the duct to seal the package.

25 3. In a sealed package, the combination of a 30 container having a rim at the mouth thereof and screw threads below the rim, a rubber dispensing member frictionally fitted into the mouth of the container and having a flange portion adapted to overlie and engage the rim to seal 35 said container at the rim and having a substantially smooth upper surface provided with an aperture extending through said member for dispensing the contents of said container in small quantities, the aperture being of capillary dimensions at the smooth surface and being larger 40 at the bottom of said member to expedite the flow of the contents to the top of the aperture and to facilitate application of the contents to the wound by direct contact of the smooth upper 45 surface therewith, and a closure cap having a

cover part provided with a downwardly depending projection on the underside thereof adapted to be forced into the aperture and having a skirt provided with screw threads for engaging the screw threads of said container, the underside of the cover part being adapted to engage and force the flange of said resilient member overlying the rim of the container into sealing engagement with the rim of the container.

5 4. A sealed package comprising in combination 10 a threaded container having an opening larger than desired for dispensing purposes and a rim surrounding the opening, a resilient member having a substantially cylindrical portion fitting into said opening and having an integral flange portion 15 engaging said rim to provide a gasket for sealing the container, said member having an aperture therein for dispensing the contents of the container drop by drop, and a closure cap having a cover portion provided with a depending 20 projection on the underside thereof and having a depending skirt provided with threads for engaging the threads of the container, said projection fitting into said aperture and the underside of said cover portion engaging the flange 25 portion of said member to seal the container.

5 5. A sealed package comprising, in combination, a container having a screw thread, a resilient member secured to said container, said member having a portion fitting against the rim 30 of said container and having a duct extending longitudinally therethrough, the upper end of said duct being of capillary dimensions for a short portion only thereof, said portion with the capillary dimensions terminating flush with 35 the upper end of said resilient member to facilitate application of the contents to a wound by direct contact of the upper end of the resilient member therewith, the portion of the duct below said capillary end being larger to form a cavity 40 to facilitate the flow of the fluid to the capillary end, and a screw closure threaded on the container to seal the package.
